UNITED STATES PATENT OFFICE.

WILLIAM H. MORGAN, OF MARSEILLES, ILLINOIS, ASSIGNOR OF ONE-HALF TO PETER HYLAND PROCTOR, OF MARSEILLES, ILLINOIS.

THIMBLE FOR REPAIRING BOILER-TUBES.

1,285,313.

Specification of Letters Patent. Patented Nov. 19, 1918.

Application filed May 14, 1918. Serial No. 234,564.

To all whom it may concern:

Be it known that I, WILLIAM H. MORGAN, a citizen of the United States, residing at Marseilles, in the county of La Salle and 5 State of Illinois, have invented a new and useful Thimble for Repairing Boiler-Tubes, of which the following is a specification.

It is the object of this invention to provide 10 novel means for reinforcing or patching, internally, a boiler tube which has become weakened, and to provide a novel process whereby such a result may be brought about.

It is within the province of the disclosure 15 to improve generally and to enhance the utility of devices of that type to which the present invention appertains.

With the above and other objects in view 20 which will appear as the description proceeds, the invention resides in the combination and arrangement of parts and in the details of construction hereinafter described and claimed, it being understood that changes in the precise embodiment of the invention herein disclosed can be made within 25 the scope of what is claimed, without departing from the spirit of the invention.

In the accompanying drawings:—

Figure 1 shows in side elevation, a device 30 constructed in accordance with the present invention, parts being broken away, the structure being mounted in a boiler tube and about to be advanced;

Fig. 2 is a cross section on the line 2—2 of Fig. 1;

Fig. 3 is a view similar to Fig. 1 but showing the parts as they will appear after the device has been advanced to the point of application;

Fig. 4 is a perspective showing one end of 40 the pusher; and

Fig. 5 is a longitudinal section showing a slightly modified form of the invention.

In the accompanying drawings, the numeral 1 indicates a boiler sheet carrying a 45 tube 2.

In carrying out the present invention there is provided a trough shaped member 3 and a trough shaped member 4, members 3 and 4 preferably being made of metal, and having 50 some resiliency. The members 3 and 4 are provided with co-operating longitudinally inclined edges 5, so that, in effect, the trough shaped members 3 and 4 are wedged shaped. The trough shaped member 4 is curved transversely, as shown at 6, upon a slightly shorter radius than is the trough shaped member 3,

so that, whereas the trough shaped member 3 fits closely and frictionally in the tube 2, the trough shaped member 4 fits somewhat loosely therein, the engagement between the member 3 and the tube 2 designated by the 60 numeral 7 in Fig. 2, and the relation existing between the member 4 and the tube 2 being denoted by the numeral 8 in Fig. 2.

The numeral 9 denotes a pusher preferably 65 made up of any desired number of sections 10 and 11, the section 11 having a handle 12, and the sections being detachably connected as shown at 14. The section 10 of the pusher carries a head 15 secured at 16 to the section 70 10, and having an outer shoulder 17 and an inner shoulder 18, spaced apart longitudinally of the pusher.

In practical operation, the trough shaped members 3 and 4 are placed in the end of the 75 tube 2 in longitudinally stepped relation, as shown at 20, the inclined edges 5 of the members coacting with each other. The inner shoulder 18 of the pusher is placed against one end of the member 4, and the outer 80 shoulder 17 of the pusher is against the corresponding end of the member 3. The parts are shown thus arranged in Fig. 1. The members 3 and 4 are advanced by the pusher in longitudinally stepped relation, as 85 indicated at 20, until the weak point in the tube 2 is reached. Then the pusher 9 is rotated until, as shown in Fig. 3, the outer shoulder 17 of the pusher bears against the end of the member 4, whereupon the member 90 4 is advanced with respect to the member 3, the member 3 remaining stationary, because it has a close frictional hold, as shown at 7, on the tube 2, the member 4 advancing readily under the action of the pusher, because, 95 as shown at 8, the member 4 does not fit so closely in the tube 2 as does the member 3. When the member 4 is advanced with respect to the member 3, the edges 5 of the members 100 coact and expand the members in the tube 2, a sealing and a reinforcement of the tube thus being brought about. Fig. 3 shows the members 3 and 4 in the position above alluded to. Since the pusher 9 is made up of any desired number of sections 10 and 11, the reinforcement 105 may be applied at any desired point between the ends of the tube 2.

In case it should be desired to patch or reinforce a boiler tube at one end, then the structure shown in Fig. 5 is resorted to. In 110 Fig. 5, parts hereinbefore described are designated by numerals previously used,

with the suffix "a." In this form of the invention, the members 4^a and 3^a are provided on their outer ends with flanges 19 which co-operate with the sheet 1^a.

5 Having thus described the invention, what is claimed is:—

1. A device of the class described, comprising a pair of trough-shaped members having longitudinally inclined edges, one of 10 said members being curved transversely upon a shorter radius than that upon which the other member is curved.

2. A device of the class described, comprising a pair of trough-shaped members 15 having longitudinally inclined co-operating edges; and a pusher having inner and outer shoulders, the inner shoulder co-operating with one member, and the outer shoulder co-operating with the other member, to advance 20 both members simultaneously in longitudinally stepped relation, the pusher being rotatable to present the outer shoulder to the first specified member, thereby to advance said member with respect to the other member, 25 after both members have been advanced

simultaneously by the pusher to a point of application.

3. A method of patching a tube, which consists in placing in the tube, in longitudinally stepped relation, a pair of trough-shaped 30 members having longitudinally inclined co-operating edges; maintaining said members in longitudinally stepped relation and advancing them together by engaging their ends with the inner and outer shoulders of a 35 pusher; rotating the pusher to shift the outer shoulder of the pusher from the end of one member to the end of the other member; and then advancing the last specified member with respect to its fellow, by the action 40 of the outer shoulder, whereby the inclined edges of the members will effect a transverse expansion of the members.

In testimony that I claim the foregoing as my own, I have hereto affixed my signature 45 in the presence of two witnesses.

WILLIAM H. MORGAN.
